wood, and Fritz E. Florschutz, Forest Hills, Pa.,
assignors to Westinghouse Electric Corpora-
tion, East Pittsburgh, Pa., a corporation of
Pennsylvania

Application December 8, 1942, Serial No. 468,234

17 Claims. (Cl. 200—88)

1

The invention relates to circuit breakers, and more particularly to overload trip devices for controlling automatic operation of the circuit breaker.

An object of the invention is to provide a circuit breaker with an improved trip device comprising an electromagnet having two reciprocably movable core members, one of which is operable to instantaneously effect tripping of the breaker upon the occurrence of overloads above a predetermined value and the other of which is controlled by a bimetal element to provide inverse time delay tripping on overloads up to the instantaneous tripping current.

Another object of the invention is to provide a circuit breaker with an improved trip device comprising an electromagnet having a plurality of movable core members, one of said core members being operable at times independently of a second core member, and at other times both core members operate simultaneously to trip the breaker.

Another object of the invention is the provision of a circuit breaker having an improved trip mechanism of simple and economical construction wherein a current responsive bimetal element acts through an ambient compensating bimetal to operate a latch and release a movable core member of an electromagnet to thereby effect tripping of the breaker.

Another object of the invention is the provision of a circuit breaker with an improved trip device comprising a solenoid having two movable core members which are operated at times simultaneously after a time delay to trip the breaker, and at other times one of the core members is operated independently of the other core member to instantaneously trip the breaker.

Another object of the invention is to provide a circuit breaker with an improved trip device including an electromagnet having interchangeable energizing coils of various ampere ratings and wherein the magnetic air gap may be varied according to the rating of the coils so that the same trip device may be used for a large number of different circuit breaker ratings.

Another object of the invention is to provide a circuit breaker with an improved trip device including a tripping solenoid having a latched armature the position of which may be adjusted to change the air gap without changing the latch relation.

Another object of the invention is to provide a circuit breaker with an improved thermal-magnetic trip device wherein a relatively light force

2

is required of the thermal element to effect tripping of the breaker.

Another object of the invention is to provide a circuit breaker with an improved trip device which is simple, accurate and reliable in operation and inexpensive to manufacture.

The novel features that are considered characteristic of the invention are set forth in particular in the appended claims. The invention itself, however, both as to structure and operation together with additional objects and advantages thereof will be best understood from the following detailed description of one embodiment thereof when read in conjunction with the accompanying drawing, in which:

Fig. 1 is a side elevational view, partly in section, of a circuit breaker embodying the principles of the invention;

Fig. 2 is a horizontal sectional view taken on line II—II of Fig. 1, and showing substantially a bottom view of the trip device.

Referring to Figure 1 of the drawing, the reference numeral 11 designates a base of strong insulating material which supports the various parts of the circuit breaker. A pair of terminals 13 and 15 are suitably secured to the base and each terminal has one or more terminal studs 19 secured thereto which extend through the back of the base 11 and serve to electrically connect the breaker to the circuit which it controls.

The upper terminal 13 has a contact block 21 of rigid conducting material secured thereto; and a rigid contact block 23 secured to the base is electrically connected to the lower terminal 15 through the energizing winding of the trip device 35 of the breaker, which will be hereinafter described.

The specific structures of the contact means and operating mechanism of the circuit breaker as shown, are of the same construction as the contact means and operating means fully disclosed in Patent No. 2,214,471 issued September 10, 1940, to Leon R. Ludwig and Merl E. Horn, and assigned to the assignee of the present invention. Hence only a brief description of these parts will be given in this application.

The main stationary contacts 25 and 27 are rigidly secured to the contact blocks 21 and 23, respectively; and the auxiliary stationary contacts 29 and 31 are secured to a triangularly-shaped contact platform 33 of conducting material which is mounted on the upper portion of the block 21 for limited tilting and rocking movement by means of pins 35 projecting from the opposite sides of the platform which engage in slots 37 provided in a pair of side walls 39 secured to the

block 21. The platform 33 is biased outwardly from the base 11 by a plurality of springs 41 and 43, and outward movement of the platform is limited by the engagement of the pins 35 with the outer ends of the slots 37 and by stop projections 45 carried by the platform adjacent its upper end. The platform 33 and, consequently, the auxiliary contacts 29 and 31 are electrically connected to the terminal 13 by means of a flexible shunt conductor 47.

The movable contact means of the circuit breaker comprises a channel-shaped contact arm 49 of conducting material which is rigidly secured to a pivoted switch member 51 by means of a plurality of screws 53. The contact arm 49 carries a main contact bridging member 55 for bridging the main contacts 25 and 27, and an auxiliary contact member 57 for engaging the stationary auxiliary contacts 29 and 31, the auxiliary contact member 57 being secured to the upper end of the channel-shaped contact arm 49 by a plurality of screws 59.

The main contact bridging member 55 is formed of rigid conducting material, and is loosely mounted on the contact arm 49 for limited movement relative to the contact arm toward and away from the main contacts 25 and 27 by means of a pair of studs 61 secured to the contact carrying arm 49, only one stud being shown. The free ends of the studs 61 have a pair of nuts 63 mounted thereon for limiting inward movement of the bridging member 55 toward the main contacts 25 and 27. A pair of coil springs 65 encircle the studs 61, and are disposed between the contact carrying arm 49 and the bridging member 55 for biasing the bridging member toward the stationary main contacts 25 and 27 with a predetermined force. The ends of the bridging member 55 are beveled to lie parallel with the beveled edges of the contact blocks 21 and 23, and have a pair of contacts 67 secured thereto for engaging the main stationary contacts 25 and 27.

The auxiliary contact member 57 is formed of rigid conducting material, and has an intermediate contact 69 and an arcing contact 71 secured thereto for engaging the intermediate and arcing contacts 29 and 31 of the stationary contact means.

A common flexible shunt conductor 73 electrically connects the auxiliary contact member 57 to the main stationary contact block 23. The flexible conductor 73 has its upper end clamped between the auxiliary contact member 57 and the contact carrying arm 49 by one of the bolts 59. The intermediate portion of the flexible conductor 73 is secured at two points to the bridging member 55 by a pair of screws 75. The lower end of the flexible shunt conductor 73 is secured to the lower contact block 23 by means of a bolt 71.

The switch member 51 has a yoke-shaped lower end which is pivotally mounted between the side walls of a main frame 79 by means of the pivot pin 81. The switch member 51 is movable about its pivot axis to open and closed circuit positions to open and close the contact means of the breaker by means of an operating mechanism indicated generally at 83.

The operating mechanism 83 is supported by the main frame 79 and comprises an actuating lever 85 pivoted on a pin 87 carried by the frame, and is connected to the switch member 51 by a link 89. An operating member 91 is also pivoted on the pin 87 for movement about the same axis

as the actuating lever 85. The actuating lever 85 is normally and releasably connected to the operating member 91 for movement thereby by means of a pair of latches 93 and 95, which are pivotally mounted on the lever 85 at 97 and 99, respectively. The latch 93 engages a roller 101 carried by the operating member 91, and this latch is, in turn, held in latching position by the auxiliary latch 95. The operating member 91 is adapted to be releasably held in closed circuit position by means of a main holding latch 103 which releasably engages the roller 101. The auxiliary latch 95 is provided with a curved tail-piece 105 by means of which it is released to cause release of the latch 93 and consequent tripping of the circuit breaker by the release of the actuating lever 85 from its connection with the operating member 91. When released the actuating member 85 moves in a counterclockwise direction about the pivot axis 87, causing opening of the movable contact means. During this movement, a cam surface 107 of the lever 85 engages the rounded nose of the main holding latch 103, moving the holding latch to released position to effect release of the operating member 91.

The switch member 51 and the actuating lever 85 are biased to open position by means of a pair of accelerating springs 109 (only one being shown), which are connected at their upper ends to the switch member 51 and at their lower ends to the sides of the main frame 79.

To close the circuit breaker after it has been tripped open, the operating member 91 is first moved in a counterclockwise direction about the pivot axis 87 to the open position to effect resetting of the latches and reestablishment of the releasable rigid connection between the actuating lever 85 and the operating member 91. After the rigid connection is thus established, the operating member 91 is moved in a clockwise direction to closed position by means of its handle 111 to effect closing of the contact means of the breaker. When the parts have been moved to closed position, the main holding latch 103 reengages the roller 101 to hold the operating member in closed position. It will be noted that the construction of the operating mechanism is such that the movable contact means is trip free of the operating member 91; that is, when the breaker is tripped, the contact means move to open position irrespective of the position of the operating member 91.

The mounting arrangement of the contact means is such that during opening of the breaker the main bridging member 55 is first separated from the stationary contacts 25 and 27, while the auxiliary contacts remain in engagement by reason of the outward movement of the contact platform 33 under the influence of the biasing springs 41 and 43. After the bridging member 55 has separated a predetermined distance from the main stationary contacts, the intermediate contacts 29 and 69 begin to separate. This takes place as soon as the pins 35 engage the ends of the slots 37. During this time, the arcing contacts 31 and 71 remain in engagement due to the rocking movement of the contact platform 33. After the intermediate contacts have separated a predetermined distance, the arcing contacts 31 and 71 begin to separate. During closing, the contacts engage in the reverse order, as will readily be understood. It will thus be seen that the arc formed during separation of the contacts is drawn only between the arcing contacts 31 and 71.

An arc-extinguishing structure, indicated generally at 113, is mounted on the upper portion of the base 11 for extinguishing the arcs drawn between the arcing contacts 31 and 71. The arc-extinguishing structure may be of any suitable type, but is preferably of the type fully described in Patent No. 2,243,038 of Leon R. Ludwig, issued May 20, 1941, and assigned to the assignee of the present invention.

The circuit breaker is adapted to be tripped open either manually, or automatically in response to predetermined overload conditions in the circuit, by means of a trip device indicated generally at 115.

The trip device comprises a trip lever 117 which is pivotally mounted intermediate its ends on the frame 79 by means of a pivot pin 119, and an electromagnet, indicated generally at 121, which is operable in response to the predetermined overload conditions to move the trip lever 117 to tripping position to cause automatic opening of the circuit breaker.

One arm 123 of the trip lever 117 is offset and extends inwardly toward the base 11 of the circuit breaker, and has its inner end disposed immediately above the electro-magnet 121 to be engaged and moved by a plunger of the electro-magnet to effect automatic tripping of the breaker. The arm 123 of the trip lever is provided with a projection 125 which is adapted to engage the curved tailpiece 105 of the auxiliary latch 95 to move this latch to released position upon movement of the trip lever to tripping position. The other arm of the trip lever 117 forms a handle 127 whereby the trip lever may be manually moved to tripping position to effect manual opening of the circuit breaker. A spring 129 connects the arm 123 of the trip lever 117 to an extension of the main holding latch 103 so that the spring thus serves to bias the main holding latch to latching position and the trip lever to its normal position, as shown in Fig. 1.

The electromagnet 121 comprises a stationary core member 131 threadedly engaging a cross member 133 integral with the frame 79, and a movable armature 135. The movable armature 135 is slidable vertically in a guide comprising a sleeve 137 provided at its lower end with an annular flange which fits in a counterbore in the bottom of a portion 139 of the main frame 79. The sleeve 137 is held in place by a member 141 secured by means of screws 143 to the bottom of the frame 139. The member 141 is formed integral with a U-shaped frame 145 which supports the time delay device and which is thus supported on the frame 139. A flange on sleeve 147 integral with and extending downwardly from the member 141 assists the sleeve 137 in guiding the movable armature 135. When the armature 135 is in its unattracted position (Fig. 1) it rests on a pair of rollers 149 mounted on a pivot pin 151 which is supported in the sides of the U-shaped frame 145.

A second smaller armature 152 is disposed for vertical movement in an opening in the upper end of the armature 135. The armature 152 is provided with a shoulder which normally rests on a shoulder in the armature 135. A trip rod 154 rigidly secured to the armature 152 extends upwardly therefrom through an axial opening in the stationary core 131, the upper end of the trip rod being disposed beneath the end of the arm 123 of the trip lever 117. The second armature 152 is at times operated independently of the armature 135 to trip the breaker and at other times both the armature 135 and the armature

152 are operated together to trip the breaker as will be more fully disclosed later.

The pin 151 also pivotally supports a latch lever 153 which normally is in latching engagement with a latch member 155 screwed into an opening in the lower end of the armature 135. The armature 135 is thereby restrained in its unattracted position.

Also supported in the U-shaped frame 145 is a pivot pin 157 upon which is pivotally mounted a lever 159. Rigidly secured by means of a screw 161 to one end of the lever 159 is an ambient temperature compensating bimetal element, 163. A current responsive thermal element 165 in the form of a bimetallic strip is rigidly mounted at its upper end by means of a screw 167 to a metallic block 169 which is secured in a recess in a conductor 171 having one end connected to the contact block 23 and the other end connected to the terminal 15 which in turn is connected to the terminal studs 19. The conductor makes a single loop around the magnet core 131 and 135 and the armature forms the energizing winding of the electromagnet.

Also mounted on the lever 159 is an adjusting knob 173 of insulating material having a screw insert 175 molded therein which threadedly engages the lower end of the lever 159. The inner end of the screw 175 bears against a yoke portion 177 of the U-shaped end of a lever arm 179 pivoted on the pivot pin 157. The arm 179 and the yoke portion 177 thereof are spaced from the sides of the frame 145 by means of spacers 181 (Fig. 2). Mounted on the lever 159 by means of the screw 161 which secures the ambient compensating bimetal 163 to the lever, is a spring member 183 having its lower end engaging serrations formed on the inner periphery of the knob 173 to restrain the knob in its adjusted position.

The upper end of the flat spring member 183 above the screw 161 is connected by means of a coil spring 185 to the lower end of the latch lever 153 below its pivot 151. The spring 185 biases the assembly comprising the lever 159 compensating bimetal 163 and the knob 173 counterclockwise about the pivot pin 157 to the position where the end of the screw 175 engages the yoke 177 of the arm 179. The arm 179 is prevented from counterclockwise movement by an ear 187 formed on the free end of the arm 179 resting against an adjusting screw 189 mounted in a bent-over portion 191 of the latch lever 153 and locked in position by a lock nut 193. The spring 185 also biases the latch lever 153 in a counterclockwise direction into latching engagement with the inside wall of the latch member 155. The force transferred from the spring 185 through the latch lever 153 to bias the latch lever counterclockwise to engage the latch with the latch member 155 is relatively light for the reason that the same spring 185 acting through the lever 159, screw 175, the arm 179 and the adjusting screw 189 applies a clockwise force to the latch lever. This latter force, however, is smaller than the force which urges the latch lever in latching direction, therefore only the difference between the two forces acts to move the latch lever 153 counterclockwise or to latching position.

The bimetal element 165 is insulated from the ambient compensating bimetal by means of an insulating button 195 mounted in the upper end of the latter. Both of the bimetal elements 163 and 165 deflect the same distance for a given change in ambient temperature. When the thermally responsive bimetal element 165 is heated in

response to overload currents by conduction from the increased resistance portion of the conductor 171 formed by the recess and block 169, the bimetal element deflects toward the base 11 of the breaker. During this deflection the bimetal 165 engages the insulating button 195 and rocks the compensating bimetal 163, the lever 159 and the arm 179 counterclockwise about the pivot 151. This movement of the arm 179 rocks the latch lever 153 clockwise about its pivot 151 thereby releasing the armature 135 whereupon the electromagnet, energized by the overload current traversing the energizing coil 171, attracts the armature 135 and moves it upwardly against the stationary core 131. The secondary armature 152 and trip rod 154 move upwardly therewith, the trip rod engaging the arm 123 and actuating the trip lever 117 to effect automatic opening of the breaker.

When the circuit is interrupted and the coil 171 becomes deenergized, the armatures 135 and 152 are moved downwardly to their unattracted positions (Fig. 1) by the force of gravity. As the bimetal 165 cools and resumes its normal position, the spring 195 moves the latch 153 into latching engagement with the latch member 155 and, acting through the adjusting screw 189 restores the arm 179, the lever 159 and the compensating bimetal 163 clockwise to the position shown in Fig. 1.

Rotation of the knob 173 varies the angular relation of the arm 179 and the compensating bimetal 163 and thereby varies the relation of the bimetal 163 with the bimetal element 165. This varies the amount of time delay and current required by the bimetal 165 to unlatch the armature. A pointer 174 integral with the frame 145 cooperates with the knob 173 to indicate the calibration setting.

Upon the occurrence of a short circuit or an overload of approximately 1000% or more of normal rated current the electromagnet is energized a sufficient amount to attract the secondary armature 152 and effect instantaneous tripping of the breaker independently of the armature 135 which remains latched in its unattracted position. Due to the relatively small mass of the secondary or short circuit armature 152, it will saturate during the operation and thereby prevent the generation of large magnetic forces which might cause damage to the device.

The circuit breaker including the trip device, may be used to interrupt circuits having various ampere ratings by substituting a series coil of the desired rating for the coil 171. In order to provide substantially the same magnetic tripping force for the different ratings, the air gap between the armatures 135 and 152 and the stationary core 131 is adjustable in steps according to the selected ampere rating. The air gap of the trip magnet is adjusted by rotating the armature 135 relative to the latch member 155. Since the latch member 155, in its unattracted position rests on the rollers 149, rotation of the armature 135 will raise or lower the armature relative to the stationary core member 131 depending on the direction of rotation. The inner wall of the latch member 155, including the latching surface, is made circular so that the latch 153 will engage the latch member irrespective of the position to which it is adjusted. The latch member 155 is provided with a tapped hole to receive a set screw 197 which extends through a selected one of a plurality of holes (only one being shown) properly spaced about the periphery of armature 135. The holes

in the armature 135 allow the set screw 197 to engage the tapped hole in the latch member 155 in predetermined selected places corresponding to the current rating of the particular coil 171 being used. For instance, when a series coil having a rating of say, 800 amperes, is mounted for use in the breaker, the armature 135 is rotated to bring the corresponding hole therein into alignment with the tapped hole in the latch member 155 after which the set screw 197 is replaced. In this manner the air gap of the trip magnet is adjusted for the particular value series coil which is used in the breaker.

Having described a preferred embodiment of the invention in accordance with the patent statutes, it is to be understood that various changes and modifications may be made therein without departing from some of the essential features of the invention. It is, therefore, desired that the language of the appended claims be given as reasonably broad interpretation as the prior art permits.

We claim as our invention:

1. In a circuit breaker comprising separable contacts and operating mechanism therefor, a trip device including a trip member, a solenoid having a stationary core member and an energizing winding, a plurality of movable core members having a common rectilinear axis of movement, means for positively holding one of said movable core members against movement, and a thermal element rigidly mounted on said winding to be heated thereby and operable in response to overload currents below a predetermined value for operating said holding means to release said one movable core member and permit said core member to operate the trip member, the other movable core member being operable at times independently of said one movable core member to operate the trip member.

2. In a circuit breaker comprising separable contacts and operating mechanism therefor, a trip device including a trip member, an electromagnet having a relatively large armature, a relatively small armature supported by the first named armature, means for positively holding the larger armature against operation, a thermal element supported on said electromagnet to be heated thereby and operable in response to overload currents below a predetermined value to release said larger armature and permit said electromagnet to operate both armatures to effect operation of the trip member, said smaller armature being operable independently of the larger armature in response to overload currents above said predetermined value to instantaneously operate the trip member.

3. In a circuit breaker comprising relatively movable contacts and operating mechanism therefor, a trip device including a trip member, an electromagnet comprising a core member and an energizing winding, a large armature and a relatively small armature disposed for axial movement along a common axis, means positively holding the large armature against operation, a thermal time delay device mounted on said winding to be heated thereby and operable when heated a predetermined amount in response to overload currents to release said large armature and permit the electromagnet to operate said large armature to effect operation of the trip member, said small armature being at times operable independently of said large armature to instantaneously operate the trip member.

4. In a circuit breaker comprising relatively

movable contacts and operating mechanism therefor, a trip device including a trip member, an electromagnet having an armature operable to operate said trip member, a latch member carried by said armature, means engaging said latch member for restraining said armature against operation, means for adjusting the armature relative to the latch member to vary the air gap of the electromagnet, and a bimetal element operable when heated a predetermined amount in response to overload currents to effect release of the armature.

5. In a circuit breaker comprising relatively movable contacts and operating mechanism therefor, a trip device including a trip member, an electromagnet, a relatively large armature, a relatively small armature mounted on and movable with the large armature, a latch member rotatably mounted on the large armature, means engaging said latch member to restrain said large armature against operation, time delay means including a bimetal element operable when heated a predetermined amount in response to certain circuit conditions to effect release of the large armature and permit operation of said armature to operate the trip member, said small armature being operable independently of the large armature in response to certain other circuit conditions to instantaneously operate the trip member, and said latch member being rotatable relative to said large armature to vary the magnetic air gaps of both armatures.

6. In a circuit breaker comprising relatively movable contacts and operating mechanism therefor, a trip device including a trip member operable to effect an operation of the operating mechanism, an electromagnet having a main armature, a second armature normally disposed in a recess in said main armature and operable thereby in response to certain circuit conditions to operate the trip member, said second armature being operable in response to certain other circuit conditions to operate the trip member independently of the main armature, and means supported on and movable relatively to said main armature for simultaneously adjusting the magnetic air gap of both of said armatures.

7. In a circuit breaker comprising relatively movable contacts and operating mechanism therefor, a trip device including a trip member, an electromagnet having an armature operable under certain circuit conditions to instantaneously operate said trip member, a second armature operable under certain other circuit conditions to cause said first named armature to operate the trip member, latch means for normally restraining said second armature against operation, an ambient temperature compensating bimetal mounted for movement independently of said latch means and operable to effect release of said second armature, and a thermally responsive bimetal operable when heated in response to overload currents to operate said ambient compensating bimetal.

8. In a circuit breaker comprising relatively movable contacts and operating mechanism therefor, a trip device including a trip member, a relatively large armature, a relatively small armature carried by said large armature and movable independently of the larger armature, an electromagnet comprising a stationary core member and a single energizing winding surrounding both of said armatures for moving said armatures, the larger armature when moved to attracted position moving the smaller armature

therewith to operate the trip member, and time delay means for controlling the movement of the larger armature.

9. In a circuit breaker comprising relatively movable contacts and operating mechanism therefor, a trip device including a trip member, a relatively large armature, a relatively small armature carried by said large armature, and operable independently of the large armature, a single energizing conductor surrounding both of said armatures for producing a magnetic field for moving said armatures, the larger armature when moved to attracted position moving the smaller armature therewith to operate the trip member, time delay means for controlling the movement of the larger armature, and means mounted on and movable with the large armature for varying the air gap of both of said armatures.

10. In a circuit breaker comprising relatively movable contacts and operating mechanism therefor, a trip device including a trip member, a relatively large armature, a relatively small armature carried by said large armature, an electromagnet for moving said armatures, the larger armature when moved to attracted position moving the smaller armature therewith to operate the trip member, time delay means for controlling the movement of the larger armature, and a single means for simultaneously varying the air gap of both of said armatures.

11. In a circuit breaker comprising relatively movable contacts and operating mechanism therefor, a trip device including a trip member, a relatively large armature, a relatively small armature mounted on and movable with the larger armature to operate the trip member, an electromagnet comprising a fixed core member and a single energizing winding surrounding said core member and both of said armatures for moving said armatures, and a current responsive time delay device for controlling the movement of the large armature to attracted position, said smaller armature at times being movable independently of said larger armature to operate the trip member.

12. In a circuit breaker comprising relatively movable contacts and operating mechanism therefor, a trip device including a trip member, an electromagnet having an armature movable to operate said trip member, a pivoted latch normally restraining said armature against movement, an ambient temperature compensating bimetal element for operating said latch, load reducing means between said compensating bimetal and said latch, and a thermally responsive bimetal operable when heated a predetermined amount by overload currents to actuate said compensating bimetal element.

13. In a circuit breaker comprising relatively movable contacts and operating mechanism therefor, a trip device including a trip member, an electromagnet having an armature movable to operate said trip member, latch means normally restraining said armature against movement, an ambient temperature responsive bimetal element operable to effect release of said armature, biasing means comprising a spring between the latch and the ambient responsive bimetal disposed to apply a force biasing the ambient responsive bimetal in operating direction and to apply a force biasing said latch in latching direction, a thermally responsive bimetal element heated in response to overload current and operable when heated by overload currents to actuate the ambient temperature responsive bimetal, and means

for transmitting the movement of said ambient temperature responsive bimetal to operate the latch to release the armature.

14. In a circuit breaker comprising relatively movable contacts and operating mechanism therefor, a trip device including a trip member, an electromagnet having an armature movable to operate said trip member, latch means normally restraining said armature against operation, means comprising a relatively strong spring disposed to exert unequal forces on said latch tending to bias said latch in opposite directions to latching and unlatching positions, a relatively small differential force of said spring being utilized to bias the latch to latching position, and means for operating said latch to release the armature.

15. In a circuit breaker comprising relatively movable contacts and operating mechanism therefor, a trip member, electroresponsive means for operating said trip member, a latch normally restraining said trip member against operation, a spring disposed to apply a predetermined force to said latch biasing said latch in unlatching direction, said spring applying a greater force to said latch biasing said latch in latching direction, and current responsive means for operating said latch to release said trip member.

16. In a circuit breaker comprising relatively

movable contacts and operating mechanism therefor, a trip device including a trip member, a relatively large armature, a relatively small armature carried by said large armature and operable independently of said large armature, said small armature saturating at certain value of overload current to prevent generation of large mechanical forces, and an energizing conductor for producing a magnetic field for moving said armatures, the large armature being movable to attracted position in response to predetermined conditions and moving the small armature therewith to operate the trip member.

17. In a circuit breaker comprising relatively movable contacts and operating mechanism therefor, a trip device including a trip member, an electromagnet having an armature operable to operate said trip member, a tubular latch member adjustably connected to said armature, a latch engaging an annular latch surface on said tubular latch member for restraining said armature against operation, said latch member being rotatably adjustable relative to said armature to vary the magnetic air gap, and current responsive means for operating said latch to release said armature.
